COMBINED DOORBOLT AND NIGHT LATCH

Hugh E. Anglyn, High Point, N. C., assignor of
one-half to Marvin R. Snipes, High Point,
N. C.

Application August 22, 1933, Serial No. 686,304

2 Claims. (Cl. 70—29)

This invention relates to door locks and more particularly to a combined latch and locking means of the push and pull type.

An object of this invention is to provide a door latch and lock which is so constructed that the door bolt can be locked by a latching member operable from the inside of the door, thereby preventing the movement of the latch without the use of a key.

10 Another object of this invention is to provide a latch of this character which is exceedingly simple in construction and wherein the locking means for the latch engages the door bolt operating member so as to hold this member against unauthorized movement.

15 The above and various other objects and advantages of this invention will in part be described and in part be understood from the following detailed description of the present preferred embodiment, the same being illustrated in the accompanying drawing wherein:—

In the drawing:—

Figure 1 is a detail side elevation of a lock constructed according to the preferred embodiment 20 of this invention, partly in section, mounted on a door shown in fragmentary form;

Figure 2 is a sectional view taken on the line 2—2 of Figure 1;

Figure 3 is a sectional view taken on the line 30 3—3 of Figure 2.

Figure 4 is a fragmentary side elevation of the inner end of the lock operating member showing the same engaged by a conventional key for movement of the operating member for the locking 35 member.

Referring now more particularly to the drawing wherein like numerals of reference designate corresponding parts throughout the several views, the numeral 10 designates generally a housing 40 provided with a facing plate 11 at one end thereof. The housing 10 is provided with a removable side 12 which is attached to the housing 10 as by a bolt 13 which is threaded through the plate 12 and into a block 14 which is carried by the housing 10.

45 A door bolt generally designated as 15 is slideable in the housing 10 through an opening 16 in the facing plate 11 and this door bolt 15 has a reduced stem or inner end portion 17 which is slideable through a guide 18 carried by the housing 10 and a spring 19 engages about this stem 17 and constantly urges the bolt 15 outwardly through the plate 11. The door bolt 15 is provided with a conventional bevelled outer end por-

tion 20 for engagement with a keeper or apertured plate which is adapted to be mounted in the frame of the door.

A bolt operating member generally designated as 21 is slideable transversely of the housing 10 through an opening 22 in the rear wall 23 of the housing 10 and through an opening 24 in the removable wall or plate 12. This bolt operating member in the present instance is constructed in the form of a bar which is substantially rectangular in transverse section and which is provided with a substantially V-shaped recess or cut-out portion 25. This cut-out portion 25 provides a cam surface on one side of the bolt operating member 21 and the bolt 15 has a rectangular opening 26 through which the bolt operating member 21 is slideable. The cam portion 25 of the bolt operating member 21 engages against the rear side of the rectangular opening 26 and the spring 19 has a sufficient tension so that it 75 will normally maintain the bolt 15 in projected position and will move the bolt operating member into inoperative position.

The bolt operating member 21 has a reduced inner end portion 27 on which a knob 28 of 80 suitable configuration may be mounted and the other or opposite end of the operating member 21 is also reduced as at 29 and a knob 30 may be attached to this reduced outer end portion.

The door bolt operating member 21 is held 85 against movement by means of a locking member designated 31. This locking member 31 is constructed, in the present instance, in the form of a U-shaped member 32 which is provided with a reduced lower end portion 33 and an operating 90 member 34 is loosely disposed between the parallel legs of the U-shaped member 32 and is slideable through an opening 35 provided in the plate 12. This operating member 34 is provided with a slot 36 extending transversely therethrough and this slot 36 is disposed on an angle to the vertical and a pin 37 which connects the two parallel legs of the U-shaped member 32 is loosely disposed in this slot 36. Movement of the lock operating member 34 inwardly of the 100 housing 10 will force the locking member 31 downwardly until the reduced lower end 33 is seated in a recess 38 provided in the upper surface of the bolt operating member 21.

The inner end of the lock operating member 105 34 is provided with a cam shaped extension 39 which extends through the front wall 23 of the casing or housing 10 and projects into a reduced housing 40 which is mounted on the outer face of the wall 23. The housing 40 is provided with 110

a key opening to receive a key 41 of suitable construction which is adapted to engage the cam shaped inner end portion of the operating member 24 so as to force this operating member 24 outwardly of the housing 40 thereby raising the locking member 31 out of the recess 38. The locking member 31 is slideable in a vertical direction between the block 14 and a guide member 42 disposed in spaced relation to one edge of the block 14 which constitutes a guide block. This locking member 31 is of a thickness such that it is loosely disposed between the front wall 23 of the casing 10 and the plate 12 so that it can freely slide in a vertical direction but is held 15 against horizontal movement by means of the guide members 14 and 42.

In the use and operation of this improved type of night latch and door bolt when it is desired to operate the door bolt independent of the night latch or lock the locking member 31 is raised by pulling the operating member 34 outwardly through the plate 12. This operating member 34 will hold the locking member 31 in either raised or lowered position the inclination 25 of the slot 36 being such that the weight of the locking member 31, when in raised position, will not move the operating member 34. When a person on the outside of the door desires to enter through the door the knob 30 is pushed inwardly, thereby causing the door bolt 15 to be moved inwardly of the housing 10 under the action of the cam portion 25. The same result is accomplished by a person desiring to pass through the door in the opposite direction by 30 pull on the knob 28 which will move the operating member 21 in the same direction.

Where it is desired to put on the night latch the locking member 31 is moved into locking position within the recess 38 by pushing the operating member 34 inwardly of the housing 10 and this movement will project the key engaging portion 39 of the operating member 34 into the key housing 40. When the operating member 34 is in this locked position pressure in a horizontal direction on the bolt operating member 21 will be resisted by the reduced lower end portion 33 and as shown in the drawing the locking member 31 is disposed at a right angle to the operating member 21. It will, therefore, 50

be seen that the door bolt 15 cannot be moved into released position until the locking member 31 has been raised from the recess 38. This latter movement can be accomplished by either pulling the operating member 34 from the inside of the door or by moving the operating member 34 under the action of a key such as a key 41 positioned in the key housing 40.

It is, of course, understood that various changes and modifications may be made in the details of construction and design of the above specifically described embodiment of this invention without departing from the spirit thereof, such changes and modifications being restricted only by the scope of the following claims.

I claim:—

1. A device as set forth, comprising a housing, a bolt slideable in the housing, a bolt operating member slideable transversely of the housing and engaging said bolt, means constantly urging said bolt into operative position, a bifurcated locking member disposed in the housing, means for slidably mounting said locking member in the housing, said bolt operating member having a recess to receive a portion of said locking member, a horizontally movable locking member operating member, said locking member operating member having an obliquely inclined slot therethrough, and means carried by said locking member and disposed in said slot whereby to vertically shift 100 said locking member upon horizontal movement of said locking member operating member.

2. A device as set forth, comprising a housing, a bolt slideable in said housing, a bolt operating member slideable transversely of the housing, a locking member disposed in the housing, said locking member having an elongated slot therein, an operating member for said locking member loosely disposed in said slot, said bolt operating member having a recess to receive a portion 110 of said locking member, said operating member for said locking member having an obliquely inclined slot therethrough, a pin carried by the locking member and loosely disposed in said slot, a cam shaped extension integral with said operating member for said locking member, and a key housing enclosing said extension.
